US0D1075732S

(12) **United States Design Patent** (10) **Patent No.:** **US D1,075,732 S**
(45) **Date of Patent:** **** May 20, 2025**

(54) **STAND FOR TELEVISION RECEIVER**

- (71) Applicant: **LG ELECTRONICS INC.**, Seoul (KR)
- (72) Inventors: **Bumsang Lee**, Seoul (KR); **Yongho Lee**, Seoul (KR); **Areum Kwon**, Seoul (KR); **Taejin Lee**, Seoul (KR)
- (73) Assignee: **LG ELECTRONICS INC.**, Seoul (KR)

(**) Term: **15 Years**

(21) Appl. No.: **29/893,569**

(22) Filed: **May 31, 2023**

(30) **Foreign Application Priority Data**

Dec. 12, 2022 (KR) 30-2022-0052210

(51) **LOC (15) Cl.** **14-06**

(52) **U.S. Cl.**

USPC **D14/239**

(57) **CLAIM**

The ornamental design for a stand for television receiver as shown and described.

DESCRIPTION

FIG. 1 is a perspective view of a stand for television receiver showing our new design;

FIG. 2 is a rear perspective view thereof;

FIG. 3 is a front view thereof;

FIG. 4 is a rear view thereof;

FIG. 5 is a left side view thereof, and a right side view is omitted because it is a mirror image of the left side view;

FIG. 6 is a top view thereof;

FIG. 7 is a bottom view thereof;

FIG. 8 is a perspective view showing an installed television receiver;

FIG. 9 is a rear perspective view showing an installed television receiver; and,

FIG. 10 is a rear perspective view showing cable management in use.

The broken lines in FIGS. 8 to 10 depict environmental subject matter only and form no part of the claimed design. All other broken lines indicate portions of the article that form no part of the claimed design.

1 Claim, 10 Drawing Sheets
